UNITED STATES PATENT OFFICE.

ANDREW J. KENNEDY, OF CHICAGO, ILLINOIS, ASSIGNOR TO PARKS BROS. & ROGERS, INC., OF PROVIDENCE, RHODE ISLAND, A CORPORATION OF RHODE ISLAND.

CUFF LINK.

Application filed August 16, 1924. Serial No. 732,425.

To all whom it may concern:

Be it known that I, ANDREW J. KENNEDY, a citizen of the United States of America, residing at 1309 Farwell Avenue, Chicago, 5 in the county of Cook, State of Illinois, United States of America, have invented certain new and useful Improvements in Cuff Links, of which the following is a specification.

10 This invention relates to improvements in cuff links particularly of the type which comprises separable cuff buttons.

One of the principal objects of the invention is to provide a cuff link consisting 15 in separable cuff buttons which are adapted to lie at an angle to one another to accommodate the natural slant of the cuff.

Another object of the invention is to provide a construction of cuff link consisting 20 in separable cuff buttons which can be coupled so as not to become disengaged when the cuff itself is tightened upon the arm.

Another object of the invention is to provide a cuff link consisting in separable cuff 25 buttons which can be cheaply and easily manufactured and which are of a construction permitting the fullest decoration of the head of the cuff button by engraving or by the mounting of precious stones therein.

Another object of my invention is to provide a cuff link, consisting of two cooperating 30 members, each having cooperating complementary latch portions adapted to couple said members after said portions are brought into contact with each other, preferably in a true axial line, and said members are manually tilted.

A further object of my invention is to provide a separable cuff link which can be inserted and locked in any way or in any 35 position in day-light or darkness.

A further object of my invention is to provide a construction which will function 40 without any protruding parts or levers to catch or tear the cuffs.

A further object of my invention is to provide a construction wherein the stem of the male member comprises a small head 45 and not a long projecting stem as in former types which makes insertion of the male member into the cuff a difficult operation.

A further object of my invention is to provide a workable structure having no pro-

jecting knobs or parts on the base of said 55 members so as not to interfere in any way with the placing of the usual desirable designs thereon and thus to provide a very neat finished article.

A further object of my invention is to 60 provide a separable cuff link which can be locked and unlocked by mere grasping of the bases thereof between the fingers without the necessity of inserting the fingers between the cuffs to soil or dirty them. 65

With these and other objects in view, the invention consists in a construction of a cuff link as hereinafter described and as more particularly pointed out in the appended claims. 70

In the accompanying drawings:—

Figure 1 shows a cuff link in accordance with the present invention in normal position in a shirt cuff.

Figure 2 is a section on a larger scale 75 showing the cuff buttons arranged in line with one another.

Figure 3 is a view in elevation showing the cuff buttons separate from one another.

Figure 4 is a section on the line 4—4 of 80 Figure 1.

Figure 5 is a view showing the cuff buttons in the position in which they are about to be engaged.

Figure 6 is a section on the line 6—6 of 85 Figure 1.

Figure 7 is a view of one of the cuff buttons mounted in a shirt cuff.

As illustrated in the drawings it will be seen that the cuff link consists in two cuff 90 buttons indicated generally by the reference characters A, B.

The cuff button A comprises a base a^1 , a stem a^2 and a cylindrical coupling member or head a^3 . Similarly the cuff button B comprises a base b^1 , a stem b^2 and a cylindrical coupling member b^3 . As will be seen, each stem is flat and is arranged with its greatest dimension at right angles to the cylindrical coupling member attached thereto. Each 95 cuff button is carried in the buttonhole C of the shirt cuff D as shown in Figure 7, the flat stem a^2 or b^2 serving to hold the cuff button from turning in said buttonhole. In inserting the cuff button into the buttonhole C one end of the cylindrical coupling member is first introduced through the buttonhole and the cylindrical coupling mem- 100 105

ber then passed completely therethrough. After this, the cuff button is rotated through an angle of 90 degrees so that the cylindrical coupling member lies transverse to the length of the hole, thus bringing the flat stem a^2 or b^2 into line with the buttonhole. When the two cuff buttons A and B are thus inserted in the buttonholes of the shirt cuff, the cylindrical coupling members a^3 and b^3 , when brought together, will be substantially in alignment and in position to be engaged with one another.

As is evident from the drawings, particularly Figures 4 and 5, the cylindrical coupling member b^3 has an opening at one end through which projects a plunger b^4 pressed outwardly by a spring b^5 contained within the coupling member b^3 . The open end of the coupling member b^3 is cylindrically constricted as shown at b^6 (Figs. 4 and 5) after insertion of the plunger b^4 and spring b^5 so as to retain the plunger b^4 in position. The other coupling member a^3 , as will also be seen particularly from Figure 5, is in the form of a hollow cylinder, a portion of the cylindrical surface of which has been cut away to permit the coupling member b^3 to be inserted thereinto.

The coupling members a^3 and b^3 are engaged with one another as is also shown in Figure 5 by the insertion of one end of the coupling member b^3 within the coupling member a^3 and in contact with one end thereof while the body of the coupling member b^3 lies at an angle to the body of the coupling member a^3 . The coupling member b^3 is then moved toward the coupling member a^3 , the resilient plunger b^4 being depressed by contact with the end of the coupling member a^3 to permit the member b^3 to pass entirely into the member a^3 . The position of members a^3 and b^3 when engaged is shown in Figure 6. When so engaged, the coupling members are only permitted to have a movement about one axis, that is the common axis of the two cylindrical coupling members. The two cuff buttons, however, have an angular movement about this axis which is limited in the following manner.

In order to couple the cooperating latch portions a^3 and b^3 of the cuff links A and B, it is obvious that two motions are necessary; namely (1) to bring the portion b^3 into contact with the complementary portion a^3 preferably by bringing the stems or shanks a^2 and b^2 of said links together in substantially a true axial line as explained above when the coupling member b^3 will pass into the coupling member a^3 to engage said members together, (2) after said portions a^3 and b^3 have been thus engaged to manually relatively tilt said links, when the upper edges of the sides of the hollow coupling member a^3 overlapping the upper edge

of the cylindrical coupling member b^3 , and the shank b^2 sinking into the slot a^6 will couple said members together so that it is impossible to pull them apart on a pull as would be exerted by the cuffs in use (see Fig. 1). It is obvious however, that the cuff links A and B when in this position are not securely interlocked at an angle to one another, but though coupled are free to pivot toward each other, the cylindrical coupling member b^3 revolving within the hollow coupling member a^3 .

Reference to Figures 1, 2 and 3 will show that the flat stems a^2 and b^2 have a width which is greater than the diameter of the cylindrical coupling members a^3 and b^3 . In this manner there is provided a surface or shoulder on each side of the coupling members a^3 and b^3 . As is shown most clearly in Figure 3, the shoulders b^7 and b^8 on each side of the coupling member b^3 form equal angles with the center line x , x^1 of the cuff button B. In other words, the angle E is equal to the angle F. In the case of the cuff button A, however, the shoulders a^4 and a^5 form unequal angles with the center line x , x^2 of the button A. The shoulder a^4 is positioned beyond the axis of the cylindrical coupling member a^3 and is substantially perpendicular to the center line x , x^2 , the angle G being therefore substantially a right angle. On the other hand the shoulder a^5 slopes rearwardly in such a manner that the angle H is considerably greater than any of the angles E, F, or G. As shown in Figure 1, the shoulders a^4 and b^8 are in contact with one another when the buttons A, B lie at an angle to one another in the position in which the bases a^1 and b^1 accommodate the natural slant of the cuff D. When, however, the cuff buttons A, B are substantially in a straight line position as shown in Figure 2, the shoulders a^4 and b^7 are in contact and prevent movement of the cuff buttons A and B beyond this straight line position.

The cuff buttons can be disengaged from one another by pressing on the bases a^1 and b^1 inwardly of the axis of the coupling members a^3 , b^3 . The arrows I, J shown in Figure 2 indicate the points at which pressure should be applied by the fingers to disengage the cuff buttons A and B. It will be seen that when pressure is thus applied to cuff buttons A and B, the shoulders a^4 and b^7 are in contact and, therefore, act as a fulcrum about which the cuff buttons A and B turn, such turning movement causing the cylindrical coupling member b^3 to spring out of the coupling member a^3 .

Reference to Figure 5 will show that a slot a^6 is formed in the side of the coupling member a^3 in line with the stem a^2 and immediately beyond the shoulder a^5 . When the two buttons A and B lie at an angle to

one another as shown in Figure 1, the stem b^2 of the button B enters this slot a^6 until the shoulder b^5 is in contact with the shoulder a^5 .

- 5 As has already been explained, the cuff buttons occupy this relatively angular position in accommodating the natural slant of the cuff. If at any time the cuff is tightened upon the arm of the wearer, it is obvious that the cuff will pull upon the bases 10 a^1 and b^1 of the buttons A and B and tend to separate the buttons. This separation can not be effected, however, without a relative movement of the coupling members a^3 and b^3 similar to that which is necessary in 15 engaging the members and as has already been described in connection with Figure 5.

Figure 6 shows the cuff buttons in position with the shoulder b^8 of button B in contact 20 with shoulder a^5 of button A, the base b^1 of button B not appearing in that figure since it is above the plane of the paper. It will be seen, however, that if the upper end of the coupling member b^3 is to be pulled 25 out of the coupling member a^3 , it is necessary that the member b^3 move about the point of contact of its lower end with the member a^3 as a center. In such movement, the side b^9 of the stem b^2 , which faces away 30 from the lower end of the coupling member b^3 , will come into contact with the opposing side b^{10} of the slot a^6 and effectively prevent the necessary angling movement of the coupling member b^3 in relation to the coupling member a^3 to permit disengagement 35 of the members. In other words, the buttons A and B can not be separated by a pull upon the cuff of the shirt when they lie at an angle to one another to accommodate 40 the natural slant of the cuff, and after they have become coupled with each other by bringing the complementary latch portions a^3 and b^3 together and manually tilting said members as explained above.

45 Each of the stems a^2 and b^2 is formed with a slot a^7 and b^{11} so as to provide spaced points of attachment between the stem a^2 and base a^1 of button A and between the stem b^2 and the base b^1 of button B. This permits the base a^1 or b^1 to be pierced centrally to provide for the mounting of a precious stone in the base, if such is desired. It will also be seen that the bases a^1 and b^1 55 may be engraved or otherwise decorated in any desired manner.

It is obvious that the coupling members a^3 and b^3 function as heads of the cuff links A and B and as cooperating complementary latch portions to couple said members A and B together.

Each of the cuff buttons is simple in construction and can be manufactured without the employment of expensive or special machinery.

65 It is to be understood that the construc-

tion shown herein represents only one embodiment of my invention and that changes and modifications can be made within the spirit and scope of the subjoined claims.

What I claim as new, and desire to secure 70 by Letters Patent, is:—

1. A cuff link comprising in combination separable cuff buttons each consisting in a base, a stem attached to said base, and a coupling member attached to the free end 75 of said stem, said coupling members permitting relative movement of the buttons about one axis only so that the buttons may lie at an angle to one another to accommodate the natural slant of the cuff and also permitting the buttons to be disengaged from each other by pressure applied inwardly and at one side of the said axis, the coupling member of one button being adapted to receive the coupling member of the other 80 button, and a slot in one side of the first cylindrical coupling member to receive the stem of the other button when the buttons lie at an angle as mentioned.

2. A cuff link comprising in combination 85 separable cuff buttons each consisting in a base, a stem attached to said base, and a coupling member attached to the free end of said stem, the coupling member of one button having a resilient plunger extending 90 through one end thereof and being thereby adapted to enter the coupling member of the other button, said coupling members when engaged permitting relative movement of the buttons about one axis only so that the buttons may lie at an angle to one another to accommodate the natural slant of the cuff and also permitting the buttons to be disengaged from each other by 95 pressure applied inwardly at one side of the said axis.

3. A cuff link comprising in combination 100 separable cuff buttons each consisting in a base, a coupling member, a stem connecting said base and coupling member and providing a shoulder on each side of the latter, said coupling members permitting relative movement of the buttons about one axis only so that the buttons may lie at an angle to one another to accommodate the natural slant of the cuff the extent of such relative movement being limited by engagement of the corresponding pair of said shoulders.

4. A cuff link comprising in combination 105 separable cuff buttons each consisting in a base, a coupling member, a stem connecting said base and coupling member and providing a shoulder on each side of the latter, said coupling members permitting relative movement on the buttons about one axis only so that the buttons may lie at an angle to one another to accommodate the natural slant of the cuff, and also permitting the buttons to be disengaged from each other by 110 pressure applied inwardly of the said axis,

the extent of such relative movement being limited by engagement of the corresponding pair of said shoulders.

5. A cuff link comprising in combination separable cuff buttons each consisting in a base, a flat stem attached to said base; and a cylindrical coupling member attached transversely to the free end of said stem, the coupling member of one button having a 10 resilient plunger extending through one end thereof and being thereby adapted to enter the coupling member of the other button; said coupling members when engaged permitting relative movement of the buttons 15 about one axis only so that the buttons may lie at an angle to one another to accommodate the natural slant of the cuff and also permitting the buttons to be disengaged from each other by pressure applied inwardly of the said axis.

6. A cuff link comprising in combination separable cuff buttons each consisting in a base, a flat stem attached to said base; and a cylindrical coupling member attached 25 transversely of the free end of said stem, the coupling member of one button having a resilient plunger extending through one end thereof and being thereby adapted to enter the coupling member of the other button, 30 said coupling members when engaged permitting relative movement of the buttons about one axis only so that the buttons may lie at an angle to one another to accommodate the natural slant of the cuff and 35 also permitting the buttons to be disengaged from each other by pressure applied inwardly of the said axis; a slot in one side of the latter coupling member adapted when the buttons lie at an angle to one another 40 to receive the stem of the other button and cooperating with said stem to prevent disengagement of the coupling members.

7. A cuff link comprising in combination separable cuff buttons each consisting in a base, a cylindrical coupling member, a flat stem transversely arranged to said member and connecting the same with said base, a 45 shoulder on said stem on each side of said coupling member, said coupling members permitting relative movement of the buttons about one axis only so that the buttons may lie at an angle to one another to accommodate the natural slant of the cuff, and also permitting the buttons to be disengaged 55 from each other by pressure applied inwardly of the said axis, the extent of such relative movement being limited by engagement of the corresponding pair of said shoulders.

8. A cuff link comprising in combination separable cuff buttons each consisting in a base, a cylindrical coupling member, a flat stem transversely arranged to said member and connecting the same with said base, a shoulder on said stem on each side of said 60 coupling member, the coupling member of 65

one button having a resilient plunger extending through one end thereof and being thereby adapted to enter the coupling member of the other button, said coupling members when engaged permitting relative movement of the buttons about one axis only so that the buttons may lie at an angle to one another to accommodate the natural slant of the cuff, and also permitting the buttons to be disengaged from each other by pressure applied inwardly of the said axis, the extent of such relative movement being limited by engagement of the corresponding pair of said shoulders.

9. A cuff link comprising in combination separable cuff buttons each comprising a base, a stem and a coupling member attached to the free end of said stem, a shoulder on said stem on each side of said coupling member to limit relative angular movement of the buttons when engaged, the shoulders on the stem of one button forming equal angles with the center line of the stem of that button.

10. A cuff link comprising in combination separable cuff buttons each comprising a base, a stem and a coupling member attached to the free end of said stem; and a shoulder on said stem on each side of said coupling member to limit relative angular movement of the buttons when engaged, the shoulders on the stem of one button forming unequal angles with the center line of the stem of that button.

11. A cuff link comprising in combination separable cuff buttons each consisting in a base, a stem and a coupling member attached to the free end of said stem, and a shoulder on said stem on each side of said coupling member to limit relative angular movement of the buttons when engaged, the shoulders on the stem of one button forming equal angles with the center line of the stem of that button, and the shoulders on the stem of the other button forming unequal angles with the center line of the stem of said other button.

12. A cuff button comprising a base, a stem attached to said base and a cylindrical coupling member attached to the free end of said stem, said cylindrical coupling member containing a resilient plunger extending through one end thereof.

13. A cuff button comprising a base, a flat stem attached to said base and a cylindrical coupling member attached transversely to the free end of said stem, said cylindrical coupling member containing a resilient plunger extending through one end thereof.

14. A cuff button comprising a base, a stem attached to said base, a cylindrical coupling member attached to the free end of said stem, said cylindrical coupling member containing a resilient plunger extending

through one end thereof, and a shoulder on said stem on each side of said coupling member.

15. A cuff button comprising a base, a flat stem attached to said base, a cylindrical coupling member attached transversely to the free end of said stem, said cylindrical coupling member containing a resilient plunger extending through one end thereof, and a shoulder on said stem on each side of said coupling member.

16. A cuff button comprising a base, a flat stem attached to said base, a cylindrical coupling member attached transversely to the free end of said stem, said cylindrical coupling member containing a resilient plunger extending through one end thereof and a shoulder on said stem on each side of said coupling member, said shoulders forming equal angles with the center line of said stem.

17. A cuff button comprising a base, a stem attached to said base, a cylindrical coupling member attached to the free end of said stem, said cylindrical coupling member having an opening in the cylindrical surface thereof, a shoulder on said stem on each side of said coupling member, said shoulders forming unequal angles with the center line of said stem, and a slot in one side of the coupling member in line with the stem and extending from the opening in the cylindrical surface of the coupling member to the shoulder on that side of said coupling member.

18. A cuff button comprising a base, a stem attached to said base, a cylindrical coupling member attached to the free end of said stem, said cylindrical coupling member having an opening in the cylindrical surface thereof, a shoulder on said stem on each side of said coupling member, said shoulders forming unequal angles with the center line of said stem, and a slot in one side of the coupling member in line with the stem and extending from the shoulder forming the greater angle with the center line of the stem to the opening in the cylindrical surface of the coupling member.

19. For use as part of a cuff button, a structure comprising a stem adapted to carry a base, a cylindrical coupling member attached to one end of said stem, and a slot in the other end of said stem, a shoulder on said stem on each side of said coupling member, said cylindrical coupling member containing a resilient plunger extending from one end thereof.

20. A cuff link comprising in combination separable cuff buttons, one of said buttons comprising a base, a stem and a hol-

low coupling member and the other button comprising a base, a stem and a cooperating coupling member adapted to interlock within said hollow coupling member, said coupling member permitting relative movement of the buttons about one axis only and means holding said coupling members interlocked.

21. A cuff link comprising in combination separable cuff buttons, one of said members comprising a base, a stem and a hollow coupling member and the other button comprising a base, a stem and a cooperating coupling member adapted to interlock within said hollow coupling member, said coupling member permitting relative movement of the button about one axis only and a spring yieldably holding said cooperating coupling member interlocked with said hollow coupling member.

22. A cuff link comprising in combination separable cuff buttons, one of said buttons comprising a base, a stem and a hollow coupling member and the other button comprising a base, a stem and a cooperating coupling member adapted to register within said hollow coupling member and spring actuated means operative to hold said coupling members coupled.

23. A separable cuff button comprising two cooperating members each having a head, a shank and a base, the heads of said members comprising cooperating complementary latch portions adapted to couple said members when said portions are brought into contact with each other and said members are manually tilted.

24. A separable fastener comprising two members having cooperating complementary latch portions adapted to couple said members after said portions are brought into contact with each other and said members are manually tilted.

25. A separable cuff button comprising two cooperating members each having a head, a shank and a base, the heads of said members comprising cooperating complementary latch portions adapted to couple said members when said portions are brought into contact with each other in substantially true axial alinement and said members are manually tilted.

26. A separable fastener comprising two members having cooperating complementary latch portions adapted to couple said members after said portions are brought into contact with each other in substantially true axial alinement and said members are manually tilted.

ANDREW J. KENNEDY,
